UNITED STATES PATENT OFFICE.

ANGELINE E. PICKERING, OF NEAR VIOLA, IOWA.

HENCOOP.

Application filed September 6, 1921. Serial No. 498,873.

To all whom it may concern.:

Be it known that I, ANGELINE E. PICKERING, a citizen of the United States, residing near Viola, in the county of Linn and State 5 of Iowa, have invented certain new and useful Improvements in Hencoops; and I do hereby declare the following to be a full, clear, and exact description of the invention, such as will enable others skilled in the 10 art to which it appertains to make and use the same.

This invention relates to the raising of chickens by the natural method, and the object of the invention is to provide a coop 15 for the mother hen and the brood of chickens, so constructed as to furnish clean and sanitary water and food; to allow for the separation of the chicks from the hen, when desired; to enclose the inmates during cold 20 or inclement weather, and to protect them at all times from their natural enemies.

A further object of the invention is to so construct the coop that it may be packed in a flat, compact bundle, for shipment, and 25 may be easily and quickly erected for use.

In the accompanying drawing, forming a part of this specification, Fig. 1 is a front view in perspective of a coop embodying my invention. Fig. 2 is a fragmentary view 30 from another point of observation, a part of the coop being broken away to show internal parts. Fig. 3 shows one of the screen doors. Fig. 4 shows an end section, detached. Fig. 5 illustrates the bundling of 35 the parts of the coop for shipment.

In practice the coop is best made of galvanized (or suitably painted) sheet steel. The sill 5 is here shown as a rectangular frame of angle-steel, within which is set the ends 40 6, the rear panel 7, and an intermediate front door-jamb 8. The rear panel is simply a flat sheet, preferably "hemmed" at the upper edge to give additional stiffness, and adapted to be bolted, as by stove-bolts, to 45 the end sections. These latter are angled at 6^a, front and rear, and may be flanged at 6^b for stiffness, if desired. They are pierced at 6^c to receive bolts 9, which fasten them to the sill, and in the same way to the 50 roof 10, which is a flat sheet, flanged on all sides to enclose the other parts. The middle jamb for the doors 11 is most conveniently fastened in place in the same manner. This should be stiffened, as by hemming the 55 edges. It is provided with a suitable door-

catch 11^a, and with means for holding the screen panels in place, here shown as simple buttons 11^b.

To the fronts of the end sections are attached hinge-members 6^d, to be engaged by 60 the pins of hinge members 12^a of the doors 12. It will be understood that the doors may be detached by simply lifting them. On the opposite side of each door a lug 12^b engages the catch. For the sake of stiffness, 65 and also to give plenty of room for the screen panels, the edges of the doors are flanged, as shown. The doors are shown overlapping the jambs at both sides, and filling the space between the sill and the roof- 70 flange. This gives the openings roominess, which is desirable, but is mainly advantageous in the matter of economy of construction, no cutting into a sheet of metal being required, nor an extra strip attached, 75 to form a lintel. The doors are of course useful in inclement weather. At other times the closures are screen-wire panels 13 fitting into the front openings. The frame 13^a of the screen is shown as made 80 of folded sheet metal, from which lugs 13^b may be punched to engage the edges of the door-jambs. They are fastened by turn-buttons 11^b. The construction admits of the doors being closed without removing the 85 screens.

For sanitary and other reasons it is preferable to floor the coop. The floor is made in two sections, 14, flanged at the sides, and normally resting on the edges of the flanges 90 and the bottom flange of the sill. One of the sections terminates at one side of the middle door-jamb, and the other section a little short thereof, so as to leave a narrow gap at 15, to receive the lower edge of a partition 16, used to keep the hen out of the compartment occupied by the chicks, the one at the right as herein shown. Provision is made for the removal of the partition, when it may be desired to throw the whole 95 100 coop into one compartment, and the partition itself is partially cut away at 16^a, on one side, so that when this side is turned downwardly the chicks may run freely to the hen, but the latter cannot pass into 105 their quarters. When the partition is reversed the occupants of both compartments are confined to them, respectively. The partition is shown supported by an open fold 16^b engaging a similar reverse fold 17^a on 110

a triangular fixed partition 17 attached to the roof by bolts at 17^b through a flange 17^c.

A trough 18, which is hung to a side wall by hooks 18^a, through holes therein, supplies food to the chicks. A shorter food receptacle 19 serves the same purpose for the hen. Along the back of the coop inside runs a water-trough 20 receiving its supply of water from a fountain 21 of a familiar type, employing a float to maintain a uniform water-level in the trough. The details of this fountain form no essential part of this invention.

Air for ventilation is supplied through 15 suitable port-holes 22.

The construction is such that the hen and her brood may be easily and conveniently kept in a healthy and thriving condition through the brooding season. It is to be noted that the floor may be removed for 20 cleaning, or when it is desired for the inmates of the coop to be on the bare ground.

For transportation the disassembled coop may be packed in a comparatively small, 25 flat bundle, as shown in Fig. 5. In this case the bottom-plates are turned the other side up from that shown in Fig. 3, the back, ends, doors, screens, middle jamb and partitions placed therein, and the whole covered with 30 the roof. The food and water parts form another bundle, easily portable, and occupying comparatively small shipping and storage space.

Having thus described my invention, I 35 claim:

1. A hen-coop provided with a pair of front doors, a pair of floor sections removable through said doors, and an interposed reversible partition slidable through one of the doors, and cut away on one side to pro-

vide a passage-way for chicks only, and when reversed, preventing such passage.

2. A hen-coop having an inclined roof, a triangular section of partition permanently attached near the roof, to form a rectangular opening below, and a removable partition fitting said opening, one side of the partition being cut away to form a passage for chicks, and the other side being straight to form a closure for the chicks when inverted.

3. A hen-coop provided at one end with a feed-trough for chicks, and at the other end with a hen's feed receptacle, a watering-trough extending into both the hen's and the chicken's compartments, a front door and a removable and reversible partition insertable through said door, whereby the coop may be used as a single enclosure, a double enclosure, with a passageway between for 60 chicks, or an exclusive double enclosure.

4. A knock-down hen-coop, comprising a rectangular sill-frame, end-sections with inclined upper ends to fit inside the sill-frame, a connecting back-plate, an outwardly flanged roof plate to enclose the upstanding parts, a door-jamb attachable to the sill and roof, detachable doors, a detachable floor in sections nearly meeting at one side of the jamb and a detachable and reversible partition held in place at the bottom by the floor sections, with means substantially as described for connecting the several parts.

In testimony whereof I affix my signature in presence of two witnesses.

ANGELINE E. PICKERING.
